(57) **CLAIM**

The ornamental design for a catch, as shown and described.

DESCRIPTION

FIG. 1 is a front perspective view of a catch showing my design;

FIG. 2 is a rear perspective view thereof;

FIG. 3 is a front elevational view thereof;

FIG. 4 is a rear elevational view thereof;

FIG. 5 is a left side elevational view thereof, the right side elevational view being a mirror image;

FIG. 6 is a top plan view thereof, the bottom plan view being a mirror image;

FIG. 7 is an exploded perspective view therefore, showing the claimed design parts separately for clarity;

FIG. 8 is an exploded right side elevational view thereof, the left side elevational view being a mirror image thereof;

FIG. 9 is an exploded top plan view thereof, the bottom plan view being a mirror image thereof; and,

FIG. 10 is a perspective view thereof, with the article shown in its environmental use.

The broken lines showing of the screws in FIGS. 1-10 and the environmental structure in FIG. 10 are for illustrative purpose only and form no part of the claimed design.
